UNITED STATES PATENT OFFICE

2,301,496

FUEL PUMPING SYSTEM

Loyd I. Aldrich, Wyoming, Ill.

Application March 24, 1941, Serial No. 384,827

8 Claims. (Cl. 103—42)

My present invention relates to a fuel system for fuel or other liquid having a pump so designed as to eliminate noise.

One object of the invention is to provide a pump which is of comparatively simple construction and which has features of design which give the effect of an air chamber as used in connection with water pumps or the like to eliminate the noise resulting from unequal flow of liquid as the impellers of the pump successively pass the outlet of the pump. In this connection, it may be mentioned that impeller type pumps, such as those embodying a pair of meshing gears, have heretofore been used extensively for the pumping of fuel oil under pressure to a burner nozzle. Considerable noise has been experienced in the operation of such pumps where a pressure relief valve acts as a by-pass to return fuel in excess of that required for operation of the burner nozzle usually from the outlet of the pump directly to the intake thereof. Such noise is amplified particularly when the supply tank is nearly empty, due to being transmitted into the tank and the ends thereof acting as diaphragms responding to the periodic changes in fuel velocity as it flows to the pump.

Another object, therefore, of my present invention is to provide a pump wherein voids in the fuel are generated by an arrangement which "starves" certain liquid pockets in the pump by creating a vacuum in such pockets and thereby vaporizing the higher ends of the fuel until the voids are eliminated by pressure produced at the outlet of the pump.

Still another object is to provide an ordinary gear pump or the like with an auxiliary intake for fuel from the source of fuel supply, such auxiliary intake being so located with respect to the main intake and the outlet of the pump that it supplies the fuel required and permits operation of the pump in such fashion that the voids above referred to are generated.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a

preferred and desirable embodiment of the invention in the accompanying drawing, in which:

Figure 1 is a semi-diagrammatic view showing my pumping system used in connection with an oil burner nozzle which is shown in section, and

Figure 2 is a diagrammatic view of a slightly modified form of pump.

In the accompanying drawing, I have used the reference numeral 10 to indicate an air blast tube of an oil burner, and the reference character NV to indicate generally a nozzle valve therein. The nozzle valve NV includes a nozzle tip 12 for spraying oil into the blast of air to produce a combustible mixture, and a by-pass and nozzle opening valve arrangement including a valve stem 13 and a valve plunger 14. The valve stem 13 is normally held seated against a seat 15 by a spring 16. The spring 16 may be adjusted by means of a rod 17 to the desired pressure of fuel oil discharged from the nozzle tip 12.

A supply pipe 18 is connected with the nozzle valve NV for supplying oil through a strainer 19 to the valve seat 15 and to the interior of the piston 14. Such oil acts against the inner end of the piston 14 to first force it toward the right in Figure 1 against the tension of the spring 16, thereby opening the nozzle valve at 13—15 and finally permitting by-pass of some of the fuel oil through ports 18 into an enlarged space 19 of the nozzle valve NV. The oil then flows through a pipe 20 to a return line 21. The spring 16 will balance the pressure of oil supplied from the pipe 18 to maintain a given pressure (somewhat lower than supplied by the pipe) of discharge from the nozzle tip 12. The excess oil is then returned or by-passed through 18, 19, 20 and 21 to the pump.

The pump itself is indicated generally at P and includes a casing 22 having a pair of impellers therein indicated at 23 and 24. The impellers are shown as of the meshing gear type, although they may be of any suitable shape. The casing 22 has a main inlet 25 with which the return pipe 21 communicates, an outlet 26 with which the pipe 18 communicates and an auxiliary inlet 27 with which a fuel supply pipe 28 communicates. The pipe 28 extends from a source of fuel supply, such as a tank T.

The main inlet 25 and the outlet 26, it will be noted, are located, as usual, opposite each other and substantially in alignment with the meshing teeth of the impellers 23 and 24. The auxiliary inlet 27 constitutes my novel contribution to the art for producing a silently operating pump. The

auxiliary inlet 27 is located a distance spaced from the main inlet 25, which is greater than the distance between the outer end of two adjacent teeth of the impeller 24. Accordingly, the auxiliary inlet 27 is at all times sealed by at least one impeller tooth from direct communication with the main inlet 25 and likewise from direct communication with the outlet 26.

My arrangement can be somewhat modified, for instance as shown in Figure 2, wherein a second auxiliary inlet 27a is provided for the impeller 23 and the fuel supply pipe 28 extends to both this auxiliary inlet and the auxiliary inlet 27. A more mechanically balanced arrangement is thus secured.

Practical operation

In the operation of my pumping system, assuming that the capacity of the pump at the outlet 26 is fifteen gallons per hour (15 g. p. h.), as indicated on the drawing, and that the nozzle tip 12 at the pressure set by the spring 16 discharges one gallon per hour, then fourteen gallons per hour would be by-passed and returned through the pipe 21. Therefore each impeller 23 and 24 picks up seven gallons per hour from the main inlet 25, whereas actually the capacity of each impeller is eight gallons per hour. The impeller 23 will accordingly generate voids 29 between any pair of teeth not in communication with the main inlet 25 or the outlet 26. In a similar manner, the impeller 24 will generate a void as at 30 between any pair of teeth not communicating with the main inlet 25 and the auxiliary inlet 27, but each pocket between adjacent teeth between the auxiliary inlet 27 and the outlet 26 will be filled to capacity (eight gallons per hour). The additional gallon per hour is supplied by the supply line 28, which gallon is added to the seven received from the main inlet 25.

The voids 29 and 30 are generated by a vaporizing action which takes place because of the vacuum created and which has the effect of vaporizing the higher ends of the fuel oil. The voids 29 and 30 thus serve in the capacity of minute air chambers to absorb the shock of variations in rate of liquid flow caused by the alternate meshing and unmashing of the teeth of the impellers 23 and 24. As soon as the pockets between the gear teeth communicate with the outlet 26, however, the oil is then under pressure to eliminate the voids and prevent them from interfering with the atomizing action at the nozzle tip 12.

In Figure 2 a better mechanically balanced arrangement is illustrated, although I have found that operation of the arrangement shown in Figure 1 is satisfactory and less complicated of manufacture. My arrangement gives the effect of an air chamber in the outlet line from the pump which is satisfactory in connection with pumping water or the like, but in connection with oil is inoperable because the air is absorbed by the oil and finally eliminated, as well as interfering with atomization of the oil at the nozzle tip.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. In a fuel pumping system, a gear type pump,

a discharge nozzle connected with the outlet thereof, a pressure relief valve between said nozzle and said outlet, a return line from said pressure relief valve communicating with the main inlet of said pump, and an intake for supplying additional liquid fuel to said pump, said intake being connected with a source of liquid fuel and being located to discharge into the space occupied by one of the gears of said pump at a point spaced a distance from said main inlet which is greater than the distance between the outer ends of two adjacent gear teeth.

2. In a liquid pumping system, a pump casing, a pair of meshing impellers therein, a liquid discharge element connected with the outlet of said casing, a pressure relief valve between said element and said outlet, a return line from said pressure relief valve communicating with the main inlet of said casing, and an auxiliary inlet for supplying additional liquid to said pump, said auxiliary inlet being connected with a source of liquid supply and being located to discharge into the space in said casing occupied by at least one of said impellers at a point spaced from said inlet and outlet a greater distance than the distance between the outer ends of two adjacent impeller blades.

3. In a fuel pumping system, a casing having an inlet and an outlet, gear type impellers therein and meshing with each other, a discharge nozzle connected with said outlet, a return line from said nozzle to said inlet, and an auxiliary inlet for supplying additional fuel to said pump, said auxiliary inlet being connected with a source of fuel and being located to discharge into the space occupied by at least one of said gears at a point spaced a distance from said inlet and outlet greater than the distance between the outer ends of two adjacent gear teeth.

4. In a liquid pumping system, a pump, having an inlet and an outlet arranged opposite each other, a pair of intermeshing impellers in said casing, a discharge pipe connected with said outlet, a pressure relief valve between said nozzle and said outlet, a return line from said pressure relief valve communicating with said inlet, and an intake for supplying additional liquid to said pump, said intake being connected with a source of liquid and being located to discharge into said casing at a point spaced a distance from said inlet which is greater than the distance between the outer ends of two adjacent impeller blades.

5. A noiseless pump for supplying fuel oil or the like to a discharge nozzle having a by-pass line comprising a casing, a pair of meshing impellers therein, said casing having an outlet and a main inlet oppositely arranged substantially in alignment with the meshing teeth of said impellers, said outlet being connected to said nozzle, said main inlet being connected with said by-pass line and said casing having an auxiliary inlet connected with a supply of fuel and located to communicate with one of said impellers at a point so circumferentially spaced from said outlet and from said main inlet as to be at all times separated by the impeller blades from direct hydraulic communication with said outlet and said main inlet.

6. A noiseless liquid pump to supply liquid to a discharge nozzle having a relief pressure actuated return line comprising a casing, a pair of meshing gears therein, said casing having an outlet and a main inlet oppositely arranged substantially in alignment with the meshing teeth of said gears, said outlet being connected with

said nozzle, said main inlet being connected with said return line, and an auxiliary inlet connected with a supply of liquid and located to communicate with one of said gears at a point circumferentially spaced from said outlet and 5 said main inlet to be at all times out of direct hydraulic communication therewith, with at least one tooth of a gear interposed between said auxiliary inlet and said main inlet and at least one tooth of said gear interposed between said 10 auxiliary inlet and said outlet.

7. In a noiseless pump for liquid supplied to a nozzle or the like having a return line, a casing, an impeller therein, said casing having an outlet and a main inlet arranged respectively to 15 supply liquid to said nozzle and receive less liquid from said return line, and an auxiliary inlet to said casing connected with a supply of liquid and

located to communicate with said impeller at a point intermediate the outlet and inlet of said pump.

8. In a noiseless pump for liquid supplied to a nozzle having a relief pressure actuated return line, a casing, a pair of meshing gears, said casing having an outlet and a main inlet oppositely arranged substantially in alignment with the meshing teeth of said gears, said outlet being connected to said nozzle, said main inlet being connected with said return line, and an auxiliary inlet to said casing connected with a supply of liquid and located to communicate with at least one of said gears at a point circumferentially spaced from said outlet and said main inlet.
